US0D1027987S

(12) **United States Design Patent** (10) Patent No.: **US D1,027,987 S**
(45) Date of Patent: ** May 21, 2024

(54) **DISPLAY SCREEN OR PORTION THEREOF WITH GRAPHICAL USER INTERFACE**

(71) Applicant: **AMBER AI LIMITED**, Hong Kong (CN)

(72) Inventors: **Yi Bao**, Hong Kong (CN); **Jian'an Xiao**, Hong Kong (CN); **Heyuan Hong**, Hong Kong (CN)

(73) Assignee: **AMBER AI LIMITED**, Hong Kong (CN)

(**) Term: **15 Years**

(21) Appl. No.: **29/845,456**

(22) Filed: **Jul. 7, 2022**

(51) LOC (14) Cl. **14-04**

(52) U.S. Cl.

USPC **D14/485**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
